UNITED STATES PATENT OFFICE.

OSCAR P. HAMMARLUND AND EMIL LARSON, OF CHICAGO, ILLINOIS.

SASH-HOLDER.

SPECIFICATION forming part of Letters Patent No. 404,537, dated June 4, 1889.

Application filed October 30, 1888. Serial No. 289,523. (No model.)

To all whom it may concern:

Be it known that we, OSCAR P. HAMMARLUND, a subject of the King of Sweden, and EMIL LARSON, a citizen of the United States, 5 residents of Chicago, in the county of Cook and State of Illinois, have invented a new and useful Improvement in Windows, of which the following is a specification.

Our invention relates to an improvement 10 in windows which are opened and closed by raising and lowering, and our improvement is especially designed for use in car-windows.

As car-windows are ordinarily constructed they are the cause of much trouble and annoyance owing to rattling or to difficulty in raising and lowering them. In order that they shall not rattle with the movement of the car, it is necessary that they shall fit snugly in the casing; but while this tends to obviate 15 one difficulty it gives rise to another, since under the effects of the weather the wood is liable to swell, causing the window to bind in its casing, and causing great difficulty in the matter of opening and closing. Other 20 effects of the weather are to cause shrinkage of the wood, so that if even moderate allowance is made to compensate for swelling the additional space between the sash and its casing produced by the shrinkage of the former 25 will cause it to rattle when the car is in motion and admit drafts and dust. Another objection to car-windows as commonly constructed is due to the disposition of the lifts and catches which make it necessary to use 30 both hands in raising the sash.

Our object is to overcome the difficulties above enumerated by providing a window which while it fits snugly in its casing will not be caused to bind by the swelling of the 35 sash or admit dust or rattle when there is shrinkage. It is further our object to provide a window with fastening means whereby it may be secured when closed or at any desired height; and it is still further our object 40 to provide a window which may be readily raised with one hand.

To these ends our invention consists in the general construction of our improvement, and it further consists in details of construction 45 and combinations of parts.

In the drawings, Figure 1 is a view in elevation of a portion of the inside of a railway

passenger-car provided with a window of our improved construction; Fig. 2, a broken partly sectional view in elevation of a window of our improved construction, showing the window-rail and window-stile; and Fig. 3, a section on the line 4 4 of Fig. 1, enlarged and viewed in the direction of the arrows, illustrating a detail.

A is a car-window, of which B is the lower window-rail and C C' the widow-stiles. One of the stiles C is provided in its edge with a longitudinal groove t, and flat springs s s' are secured within the groove, preferably in the 55 positions shown.

D is a strip, preferably of wood, which fits the groove t, resting at its inner edge toward opposite ends against the springs s s', its outer edge projecting normally beyond the edge of 60 the stile C. Toward one end the strip D carries on its inner edge a stud r, arranged to enter a socket r' in stile C, as shown. Toward its opposite end the strip D is provided with a projecting friction-surface q, which may be 65 afforded by a strip of soft rubber countersunk in the outer edge of the strip D and secured. A stirrup p passes around the strip D, preferably under the friction-surface q, and is provided with projecting ends which 70 embrace the end of a rod E, to which they are connected, as hereinafter described.

The rod E is provided at its end which engages the stirrup p with a lip o, and at its 75 opposite end is formed into a yoke o', as shown. The rod E is housed in an opening or bore n in the lower window-rail, which extends, preferably, to the longitudinal center of the rail, where it meets an opening n' in the inner face of the latter.

F is a handle comprising a sleeve portion m, having a flange m', provided with screw-holes, and surrounding a shank k, capable of being turned within the sleeve m by means of the hand-hold k², and secured against removal therefrom by a disk k'. The handle F is secured at the flange m' to the window-rail B, the end provided with the disk k' extending into the opening n'. Pins k³ project eccentrically from the face of the disk k' and 85 engage the yoke o', as shown. When the window is in operative position, the strip D is caused by the springs s and s' to bear 90 against the window-post and press the edge 95 of the window-rail B against the flange m' of the handle F.

of the window-stile C' into its seat in the casting at the opposite side of the window.

The spring s, while it must necessarily possess sufficient resilience to prevent rattling of the window, does not press the adjacent end of the strip D against the window-post with sufficient force to cause a friction between the surfaces, which would materially resist up and down movement of the window. The spring s', however, is preferably of stiffer quality, and serves in its normal condition to press the friction-surface q against the window-post with sufficient firmness to hold the window at any adjusted height. To raise or lower the window, it is therefore necessary to disengage the friction-surface q from the window-post, and this is accomplished by turning the hand-hold k², the engagement of the eccentric-pins k³ with the yoke o' causing a pin (depending upon the direction of turning) to draw the rod E, and consequently the strip D with its friction-surface q, toward the middle of the window.

It is desirable that the handle F be turned from the start against the resistance of a spring, which will cause it to return after each operation to its normal position. We therefore connect the rod E and stirrup p in the following manner to permit a limited amount of motion to the strip D, independent of the rod E. The end of the rod E, embraced by the ends of the stirrup p, is provided with an elongated slot o² to surround a pin p', which is secured at opposite ends in the stirrup p, and a flat spring s² in the slot t bears against the lip o of the rod E to hold the latter normally at the limit of its outward movement. This construction, it will be seen, prevents the contraction or swelling of the window, or the yielding or resilient motion of the strip D within certain limits, from affecting the normal position of the handle F, while the lost motion occasioned by the slot-and-pin connection is desirable, inasmuch as it increases the extent to which the handle F must be turned to disengage the friction-surface q from the window-post, and thereby prevents a too sudden release of the window. The engagement of the stud r with the slot r' prevents any longitudinal movement of the strip D in the slot t.

As with our improved construction it is only necessary, in order to open the window, to turn the handle F and raise the sash by means of the latter, ordinary window-lifts may be dispensed with and the raising effected with the employment of but one hand.

The ordinary window-catches may also be dispensed with, as, in addition to the steadiness it affords to the window, which obviates all rattling with the motion of the car, the friction-surface q serves to secure the window at any adjusted height with a firmness sufficient for all ordinary purposes.

Our improved window is applicable for street-car and other purposes where the window is opened by lowering, it being only necessary to invert the sash.

What we claim as new, and desire to secure by Letters Patent, is—

1. In combination with a window, a strip D on a lateral edge of the window-sash to bear against the window-casing, and provided on its outer surface toward one end with a projection q, a resilient medium maintaining the strip normally beyond the lateral edge of the window, with force sufficient to sustain the window at any adjusted height by the engagement of the projection q with the adjacent surface of the window-casing, a handle F, affording a window-lift located toward the middle of a horizontal rail of the window and connected with the strip D near the projection q, substantially as described.

2. In combination with a window, a strip D at the lateral edge thereof to bear against the window-casing, a resilient medium maintaining the strip normally beyond the lateral edge of the window, a rod E, loosely connected with the strip to afford lost motion, a spring maintaining the rod E normally at the limit of its outward movement, and a handle connected with the said rod and operative to retract the rod and with it the strip, substantially as described.

3. In combination with a window, a strip D at the lateral edge thereof to bear against the window-casing, a resilient medium maintaining the strip normally beyond the lateral edge of the window, a rod E, loosely connected toward one end with the strip to afford lost motion, a spring s², maintaining the rod E normally at the limit of its outward movement, a yoke o' on the opposite end of the rod E, and a handle F, carrying pins k³, engaging with the yoke o', and operative, when turned in either direction, to retract the rod E and with it the strip D, substantially as described.

OSCAR P. HAMMARLUND.
EMIL LARSON.
